UNITED STATES PATENT OFFICE.

CHRISTIAN H. SCHARAR, OF SCRANTON, PENNSYLVANIA.

CENTRIFUGAL SEPARATOR.

SPECIFICATION forming part of Letters Patent No. 517,363, dated March 27, 1894.

Application filed August 19, 1893. Serial No. 483,556. (No model.)

To all whom it may concern:

Be it known that I, CHRISTIAN H. SCHARAR, a citizen of the United States, residing at Scranton, in the county of Lackawanna and State of Pennsylvania, have invented a new and useful Centrifugal Separator, of which the following is a specification.

This invention relates to centrifugal separators; and it has for its object to provide an improved machine of this character especially adapted for the separation of coal, but which is equally as well available for use in effecting the necessary separations of salt, grain, &c.

To this end the main and primary object of the invention is to construct a separator machine on the centrifugal principle which will secure perfect separations of the material being operated upon, and which will overcome the difficulties encountered in other devices of a similar character, such as clogging of the screens, incomplete separations, and an excess of power for operating the machine.

With these and other objects in view which will at once suggest themselves to those skilled in the art, the present invention contemplates such improvements as will materially increase the usefulness of centrifugal separator machines, and these improvements will be hereinafter fully elucidated in the description, the accompanying drawings and the appended claims.

In the drawings:—Figure 1 is a central vertical sectional view of the centrifugal separator constructed in accordance with this invention. Fig. 2 is a horizontal sectional view on the line 1—1 of Fig. 1. Fig. 3 is a similar view on the line 2—2 of Fig. 1. Fig. 4 is a central vertical sectional view of a modified form of the machine, showing the several parts thereof in an inverted position. Fig. 5 is a horizontal sectional view on the line 3—3 of Fig. 4. Fig. 6 is a similar view on the line 4—4 of Fig. 4. Fig. 7 is a similar view on the line 5—5 of Fig. 4.

Referring to the accompanying drawings, A represents a stationary conical casing, open at the top and bottom and supported at its lower edge on the supporting bed or base B, which, as illustrated, is a suitable frame of strong timbers. The said stationary conical casing A, is provided at suitable points and in different horizontal planes with a series of

tangential discharge spouts C, which are disposed at a tangent to the circumference of the casing, and which may be either arranged in the same vertical plane in a line one above the other, or alternately arranged, as shown in Fig. 5 of the drawings, and in either event the said tangential discharge spouts provide means for the centrifugal discharge of the several separated portions of the material ejected from the screen devices mounted to revolve inside of said casing, and which I shall now proceed to describe.

Centrally arranged on the supporting bed or base B, is a step bearing D, which receives the lower end of the tubular vertical shaft d, is journaled at its upper end in a suitably supported bearing d', in a line with the step bearing D, and by reason of the said shaft being tubular, the bearing D, in which it moves, may be readily lubricated. The vertical screen shaft d, is provided at a point intermediate of its ends with the supporting collar d², at a point above and adjacent to which is located an oil hole d³, which provides means for lubricating the revolving sleeve E, mounted on the shaft d, for revolution and supported thereon by the collar d². The sleeve E, has attached to the upper end thereof the drive pulley e, by means of which motion is communicated to said sleeve in a direction opposite to the rotation of the shaft d, which is driven by the drive pulley e', secured thereto directly above the upper end of the shaft sleeve E. The revolving screen shaft E, has attached at suitable points thereon the small spider frames F, which are carried around with the revolution of the sleeve, and have securely bolted to their outer flanged ends f, the tapered hopper tube G. The tapered hopper tube G, extends inward to a point about in a line with the lower end of the sleeve E, and is of a larger diameter at its inner open end than the outer or upper receiving end thereof, whereby a non-clogging feed of the material may be insured. The said tapered hopper tube F, not only provides means for feeding the screen devices with the material to be separated, but also provides for connecting said screen devices with the shaft sleeve E, in order that motion may be communicated to the screen devices which revolve therewith.

The hopper F, therefore has secured to the outside thereof the screen spiders H, having the inner rings h, embracing the hopper tube and the radial series of spider arms h', extending outwardly from the rings h, and having securely attached to the outer ends thereof the inner flanged ends h², of the perforated division wings h³. The said screen spider frames H, which form the supporting frame for the revolving screen, are suitably spaced apart so as to dispose the perforated division rings h³, a distance apart from each other whereby the necessary separations may be effected by the machine, and said perforated division rings 15 h³, are disposed in horizontal planes, and nearly register with the diameter of the stationary conical casing A, at the points where they are located, so that they may freely turn inside of said casing, while at the same time preventing any material from working its way over their edges to the space below the same. As clearly illustrated in Fig. 1, of the drawings, the perforated division rings h³, are disposed in the same horizontal plane as the 20 bottom of the tangential discharge spouts C, which communicate with the spaces directly above said rings, thereby providing means for an easy discharge of the material, which works its way onto the rings. As noted, the 25 inner ends of the division rings h³, are flanged as at h², and to these inner flanges of the said rings are secured the edges of the screen sections I and I'. The screen sections I and I', are arranged in perfect alignment so as to 30 form a conical separating screen adapted to be rotated or revolved inside of the outer stationary casing A, and as clearly illustrated in the drawings, the lower screen section I', is of a finer mesh than the upper section I, and 35 forms a greater part of the separating screen, so that the dirt and other waste material may readily find escape from the machine before the good material is graded by the upper coarser screen I. It is to be understood that 40 the rotary screen, formed by the aligned screen sections I and I', is to consist of the most improved form of material such as perforated iron or woven wire screen cloth, and may be either plain or corrugated, and while the 45 rotary screen, formed by the aligned screen sections I and I', is to consist of the most improved form of material such as perforated iron or woven wire screen cloth, and may be either plain or corrugated, and while the 50 screen is constructed in a conical form, it will be apparent that the same results will be secured by having the periphery of the rotary screen polygonal or circular. The number of screen sections which comprise the rotary 55 screen is of course varied according to the number of separations to be effected, and depends entirely upon the character of the work. The lower finer mesh screen section I', which has the upper edge thereof secured to the inner flanged end of the lower one of the division rings h³, has its lower edge securely bolted to the upwardly extending attaching flange J, projecting integrally from the screen bottom disk j. The screen bottom disks j, loosely 60 embraces the vertical screen shaft d, and nearly registers in the lower open end of the stationary casing A, so as to close in the bottom

thereof, while at the same time freely turning therein with the screen and providing for the centrifugal discharge of the dust and fine waste material out of the lower one of the tangential discharge spouts C, which communicates with the space between the outer ring portion j' of the bottom disk beyond its flange J, and the intermediate or lower one of the perforated division rings h³. While the disk j, serves to inclose the bottom of the rotary screen, the top thereof is closed in by the top canopy K, secured to and supported above the upper division ring h³, by means of the bracket legs 80 k, attached thereto and to said division ring. This top canopy closes in the top discharge space of the separator and overlaps the upper edge of the outer stationary casing A, although it will be apparent that such top canopy may remain stationary and be secured to the upper edge of the stationary casing. The material introduced within the interior of the rotary screen, is distributed against the inner sides thereof by means of the bottom distributing fan and agitator L. The bottom distributing fan L, comprises the central hub l, securely clamped on the shaft d, inside of the rotary screen and at the small end thereof, and a radial series of curved spirally disposed distributing or fan blades l', the outer edges of which travel in reasonably close proximity to the inner sides of the rotary screen, and this distributing fan not only serves to distribute and throw the material out against the sides of the conical separator screen, but also maintains an outward draft through the lower one of the tangential discharge spouts, and thereby materially assisting the discharge of dust and fine waste material. The discharge of the dust and fine waste material is mainly effected by reason of a series of exterior discharge wings M. The exterior discharge wings M, are secured at their upper edges to the bottom of the intermediate one of the division rings h³, and at its lower edge to the top of the bottom disk j, outside of the lower screen section I', so as to travel in the space between the said lower screen section and the inner sides of the stationary casing A. The said discharge wings M, are outwardly curved and spirally inclined so as to work the separated waste material toward the lower one of the tangential discharge spouts C, and also maintains a current or draft downward and outward which carries with it the dust and serves to keep the meshes of the rotary screen clean. 110

Now it is thought that the construction and operation of the preferred form of my improved centrifugal separator machine will be readily apparent to those skilled in the art. Motion is first communicated to the rotary screen and the revolving distributing fan L, so that the same will revolve in directions opposite to each other, and then the coal, or other material to be separated, is introduced through the hopper G, into the rotary screen. The material falls from the hopper onto the 125 130

bottom disk N, of the distributing fan L, such bottom disk closing the spaces between the lower edges of the blades l' and being located in the same plane as one of the discharge 5 spouts. All the material is thus first dropped into the spaces between the distributing blades of the fan L, so that as the parts of the machine continue to revolve, such material will be carried around and thrown outward against the conical sides of the rotary separating screen. As the material is thrown out against the sides of the screen, it is carried upward by centrifugal force, owing to the conical shape of the screen, and by reason of the same force is held against the sides of the screen. The finer or waste portion of the material being separated necessarily finds escape through the lower finer mesh portion 15 I', of the screen, and is carried around by the wings M, and discharged at a tangent to the circumference of the casing A, through the lower one of the tangential discharge spouts C. The material continues its ascent up the sides of the conical screen and undergoes a 20 second separation in the upper portion of the rotary screen, and such separated portion works out onto the lower one of the perforated division rings h³, the perforations in which allow any dirt or small sized material, 25 carried up to that point, to fall back into the waste space there below, while the other portions of the material, which will not pass through the perforations in the rings, are discharged tangentially through the discharge 30 spout communicating with the space between the two rings. Finally, the largest sizes of the material ascend entirely over the upper edge of the screen onto the upper one of the division rings h³, from which it is discharged 35 out of the upper one of the tangential discharge spouts. It is to be noted that when the material, such as wet coal is being screened or separated, the fan L and the wings M, have a tendency to create a current outwardly, thus drying the screen and assisting in keeping the meshes thereof free from clogs, and it is to be understood that any number of fan blades and wings may be employed to effectually maintain this operation. 40

45 While I have described the preferred form of my apparatus and the incident operation thereof, still it will be obvious that such forms as shown in the modification of Figs. 4, 5, 6 and 7 may be observed without in any way affecting the principle of the invention. The construction shown in these figures is simply a direct inversion of the several parts of the separator herein described. The outer casing and the inner rotary screen are supported in inverted positions, so that the operation described for the upright construction is the reverse of that incident to the modified construction, in which the separation of the material begins at the upper portion 50 of the rotary screen and works down to the lower flared end thereof, but it will of course be obvious that such material is held

out against the sides of the screen and discharged by reason of the same centrifugal force which effects the separation in the preferred construction. 55

In view of the detailed description hereinbefore set forth it is unnecessary to detail the construction of the apparatus shown in the modification, for it is clearly shown in the drawings that the same detailed construction is observed, and therefore the several constituent parts of the separator are provided with the same letters as the corresponding parts in the preferred form. 60

As clearly shown in Fig. 4 of the drawings the screen spiders are secured directly to the vertical shaft d, so that the rotary screen may be rotated in an inverted position and the bottom disk or plate j, of the screen, is also attached to the shaft d, in the lower open end of the stationary casing so as to revolve with the screen as hereinbefore described. The reverse position of the several constituent parts of the apparatus is maintained by attaching the distributing fan L, to the shaft sleeve E in the small end of the screen, and the bottom disk N, of said fan is disposed at the lower edges of the blades so as to catch the material from the top hopper G, and thereby hold the material until it is thrown out against the sides of the screen by reason of the disposition of the fan blades and the revolution thereof. The modified construction of apparatus may also include therewith the alternate disposition of the tangentially arranged discharge spouts C, which are to be disposed in the most convenient positions for discharging the separated portions which pass therethrough. 65

Other modifications than those described might readily suggest themselves to those skilled in the art, and I will therefore have it understood that any other changes in the form, proportion and the minor details of construction may be resorted to without departing from the principle or sacrificing any of the advantages of this invention. 70

Having thus described the invention, what is claimed, and desired to be secured by Letters Patent, is—

1. In a centrifugal separator, a stationary casing having suitably arranged side discharge spouts in different horizontal planes, and a rotary separating screen mounted to revolve inside of said casing and having a series of separated exterior discharge spaces each communicating with a separate discharge spout, substantially as set forth. 75
2. In a centrifugal separator, an outer stationary casing having suitably arranged discharge spouts, a revolving conical separating screen mounted within said casing, and a revolving agitator and distributor arranged for rotation within said screen, and located at the small end of the screen to create a draft and agitate the material out to the sides of the screen, substantially as set forth. 80
3. In a centrifugal separator, a stationary

- casing having separate discharge spouts in different horizontal planes a conical rotary separating screen having separate aligned screen portions and a series of separated exterior discharge spaces communicating with the spouts, and a reversely rotating distributing fan arranged within one end of said screen, substantially as set forth.
4. In a separator machine, a stationary casing having a series of side discharge spouts in different horizontal planes a rotating conical separating screen comprising aligned screen sections of different mesh, and having a series of separated exterior discharge spaces communicating with the spouts and a reversely rotating distributing fan mounted within one end of said screen and having an imperforate bottom disk in the plane of one of said discharge spouts, substantially as set forth.
5. In a separator machine, a stationary casing having a series of side discharge spouts in different horizontal planes, a rotating conical separating screen comprising aligned screen sections of different mesh, and having a series of separated exterior discharge spaces communicating with the spouts, and a reversely rotating distributing fan mounted within one end of said screen and comprising a radial series of curved spirally disposed distributing blades and arranged in a plane with one of the discharge spouts, and an imperforate bottom disk connecting the lower edges of said blades, substantially as set forth.
6. In a separator machine, a stationary casing having suitably arranged side discharge spouts, a rotating separating screen mounted inside of the casing and having exterior division rings forming separate discharge spaces, a reversely rotating distributing fan mounted within the fine mesh portion of the screen, and an exterior series of discharge wings secured exteriorly to the fine mesh portion of the screen, substantially as set forth.
7. In a separator machine, a stationary conical casing, a top and bottom inclosed rotating separating screen mounted inside of the casing and having exterior division rings, certain of which are perforated, a reversely rotating distributing fan mounted within one end of the screen, an exterior series of discharge wings outwardly curved and spirally inclined, and suitably arranged tangential discharge spouts communicating with the spaces between said division rings, substantially as set forth.
8. In a centrifugal separator, a stationary conical casing having suitably arranged tangential discharge spouts, a rotary separating screen mounted within said casing and having exterior discharge spaces each communicating with one of said discharge spouts, a hopper tube arranged centrally within and at the top of said screen, a reversely rotating distributing fan mounted within the screen below the hopper, and an exterior series of

spirally inclined discharging wings secured exteriorly to the fine mesh portion of the screen, substantially as set forth.

9. In a centrifugal separator, a stationary conical casing having suitably arranged tangential discharge spouts, a top and bottom inclosed rotating separating screen of different mesh screen sections and having a series of separated exterior division rings working freely inside of said casing and each in line with the bottom of one of said discharge spouts, a tapered hopper tube supported centrally within the top portion of the screen and rotating therewith, an independent reversely rotating distributing fan mounted within the lower portion of the screen below said hopper tube, and an exterior series of curved and spirally inclined discharge wings arranged between the two lower division rings, substantially as set forth.

10. In a centrifugal separator, a stationary conical casing open at both ends and having suitably arranged side discharge spouts, a vertical screen shaft having a supporting collar intermediate of its ends, a shaft sleeve turning loosely on the shaft and resting at its lower end on the supporting collar, a tapered hopper tube attached to said sleeve and turning therewith, a rotary separating screen supported in position within the casing and attached to said hopper tube, a separate and independent distributing fan mounted on the shaft inside of the rotating screen, and suitable discharge devices, substantially as set forth.

11. In a separator machine, a stationary conical casing having tangential discharge spouts, a suitably arranged step bearing, a tubular vertical shaft stepped at its lower end in said bearing and having an intermediate supporting collar and an oil hole adjacent to the collar, a reversely rotating shaft sleeve loosely turning on said shaft above its collar, small spider frames attached to said sleeve, a hopper tube secured to said spider frames, a rotating separating screen supported from said hopper tube and having exterior division rings at the terminals of each different mesh and a flanged bottom disk having an outer ring portion, the distributing and discharge devices, and the top canopy supported in position over the upper open end of the screen and said casing, substantially as set forth.

12. In a centrifugal separator machine, a stationary conical casing having tangential discharge spouts, a suitably stepped vertical shaft, a reversely rotating shaft sleeve turning on said shaft, the hopper tube attached to said shaft sleeve, screen spiders embracing said hopper tube and having a radial series of spider arms, flanged division rings secured to the outer ends of said spider arms, a bottom disk loosely turning on the shaft and having an upwardly extending attaching flange, the aligned conical screen sections of different mesh having their edges secured to the flange

of the bottom disk and those of said division rings, and the discharge devices, substantially as set forth.

13. In a separator machine, a stationary conical casing having a series of tangential discharge spouts arranged in different horizontal planes, and a rotary conical screen mounted within the casing and having a series of separated exterior discharge spaces

communicating with said tangential spouts, substantially as set forth.

In testimony that I claim the foregoing as my own I have hereto affixed my signature in presence of two witnesses.
